UNITED STATES PATENT OFFICE.

FREDERIC E. WELLS, OF GREENFIELD, MASSACHUSETTS.

MOTOR.

SPECIFICATION forming part of Letters Patent No. 691,424, dated January 21, 1902.

Application filed January 25, 1901. Serial No. 44,671. (No model.)

To all whom it may concern:

Be it known that I, FREDERIC E. WELLS, a citizen of the United States of America, residing at Greenfield, in the county of Franklin and State of Massachusetts, have invented new and useful Improvements in Motors, of which the following is a specification.

This invention relates to motors, and has for its object a construction whereby water 10 may be forced by steam or other artificial pressure other than gravity from one tank through a motor into another tank alternately backward and forward, whereby continuous movement may be imparted to a motor located between said tanks; and the invention 15 consists in the construction described in the following specification, and more particularly pointed out in the claims.

I am aware that steam has been applied directly to turbines as a motive force; but it 20 has been generally with a considerable percentage of loss, and to obviate this loss I interpose between the steam-pressure and the turbine a body of water which may be applied to the turbine at any desired pressure, thus producing in a small compass a motor 25 having many of the characteristics of a turbine running under a head of water which would be represented by the pressure under 30 which the water is forced through the wheel. By the use of a relatively dense medium, like water, as compared with steam, motors of the turbine type are rendered much more effective.

35 In the drawings forming part of this specification, Figure 1 is a plan view of a construction embodying my invention, showing a portion of a steam-boiler, two tanks for containing water, a motor located in proximity thereto, and suitable pipe connections, some of the parts being broken away to more clearly illustrate the construction. Fig. 2 is a side elevation of one of the tanks and the generator shown in Fig. 1 and showing in vertical section a pressure-actuated piston whereby 40 valves pertaining to the construction may be operated.

Referring to the drawings, *a* represents a steam-boiler; *b* and *c*, water-tanks; *d*, a steam- 45 pipe connected with the boiler, and *e* and *f*

branches thereof which lead, respectively, to and are connected with the tanks *b* and *c*. The latter are so constructed as to be able to withstand the same pressure that the boiler may be subjected to.

55 Located, preferably, between the tanks *b* and *c* is a motor *g*, which is represented in the drawings as a turbine construction, which is the type of motor preferred, though the invention is not confined thereto, for a piston-motor might be used instead of the form shown. The motor is preferably located near the bottom of the tanks *b* and *c*, while the steam-pipes *e* and *f* lead into the top of said tanks. A pipe *h* connects the two tanks *b* and *c* close to the lower end of the latter, and from said pipe a branch *i* runs to the inlet-pipe of the motor *g*. Located at the junction of the pipes *h* and *i* is a three-way valve *j*, and located at the junction of the steam-pipe *d* with its branches *e* and *f* is a similar three-way valve *k*. Thus it is obvious that if the valve *k* is so turned as to permit steam to pass through the pipes *d* and *e* into the top of the tank *b* and that the valve *j* is so turned as to 60 allow a free passage from the tank *b* through the pipe *h* and its branch *i* to the motor *g* if the tank *b*, which is closed, be filled with water the steam-pressure applied to the top of the tank *b* will drive the water down through 65 the pipe *h*, the valve *j*, and the branch *i* to the motor *g*. From the discharge side of the motor *g* a pipe *l* is connected into a pipe *m*, which is in communication with both of the tanks *b* and *c*, and at the juncture of the pipe *l* with the pipe *m* is a valve *n*, which, like the valves *k* and *j*, is a three-way valve. These three valves *j*, *k*, and *n* are connected together, whereby when one is moved they will 70 all be simultaneously moved. It is thus seen 75 that the valves may be so arranged that while steam has free access to the tank *b* through the branch *e* the branch *f* will be cut off, the valve *j* may be so arranged as to allow water from either tank to flow through the branch *i* to the inlet side of the motor, and the valve *n* may be so arranged as to divert the flow of 80 the discharge either way through the pipe *m* into the tank *b* or the tank *c*. Whichever 85 way these valves are set upon the resetting 90 95 100

of one of them to a new position all of them will be simultaneously moved. Therefore in order to effect the shifting of the pressure of steam alternately into the tanks *b* and *c* at 5 the proper time means have been provided as follows for moving one of said valves—*j*, for example—which consists in prolonging the stem of said valve by means of a rod *o*, suitably supported and extending to the top of 10 the tank, on the upper end of which rod is a crank *p*, and on the valve *k* is a similar crank *q*, these two being united by a rigid connection *r*, as shown. Near the lower end of the rod *o* is a similar crank-arm *s*, connected in 15 the same manner with another arm *t* on the stem of the valve *n*. Any suitable means may be employed for imparting to the rod *o* a rocking motion, whereby said valves through their described connections may be rotated reciprocally on their axes. In the drawings a convenient means for accomplishing this is shown, which consists in utilizing a steam-actuated piston *u*, the rod of which is adjustably connected with one arm of an elbow-lever *v*, 20 whose opposite arm by means of a connection *w* is connected with a crank *x*, secured on said rod *o*. The cylinder of said piston *u* is provided with a steam-chest having an ordinary slide-valve *y* therein, the stem of which is engaged by an arm *z*, (see Fig. 2,) secured to 25 the end of a rod *1*, which enters the tank *b* and is provided with a float *2*, supported on the end of an arm which is secured to said rod *1*. Axially opposite this rod *1* is a similar rod *3* in the tank *c* and provided with a float *4*, similar to the float *2*; but in this tank *c* the float *4* is hung in a position opposite to the float in the tank *b*. On the end of the rod *3* is an arm *5*, similar to the arm *z*. These 30 two arms *z* and *5* engage a transversely-located pin in the stem of the slide-valve *y*; but the floats being hung on opposite sides of the rods on which these arms *z* and *5* are supported the rise of one float serves to elevate the 35 stem of said valve *y* and the rise of the other float will force said stem downward, thus at the proper time shifting the valves *k*, *j*, and *n*, said float being so located in each tank as to shift the valves in one direction or the 40 other whenever either one of the tanks becomes filled.

Connected with the steam-boiler *a* and with one of the tanks is a pump *6*, whereby water may be drawn from the tank and forced into the boiler.

It is apparent that there will be more or less condensation of steam by the water in the tanks *b* and *c*, especially until such time as this water shall attain a temperature near the 55 boiling-point. It is desirable that the water in the tanks should be kept as hot as possible without actually reaching the boiling-point, to the end that as little of the heat contained in the steam shall be lost as possible; but as 60 it is inevitable that the boiler should lose a

part of the water therein by condensation means are provided for returning it to the boiler.

It is apparent that when the water from one of the tanks is being forced through the motor into the other tank the receiving tank must be provided with a suitable vent, which is located in the top of each of the tanks *b* and *c* and is indicated by *7*. This vent consists merely in screwing a short sleeve into the top of the tank, in which sleeve is suspended a valve *8*, which is suitably supported by a stem extending up into the opening in the sleeve. The filling of the tank with water will close this valve, and after the tank has been so filled and steam is admitted the pressure of the steam will hold the valve in the vent closed; but as soon as the tank has been emptied the shutting off of the steam-pressure and the almost instantaneous injection of water from the other tank will cause a sufficient condensation of the steam left in the tank to cause the valve *8* to open, thus permitting it to fill again with water unobstructedly.

Having thus described my invention, what I claim, and desire to secure by Letters Patent of the United States, is—

1. The combination with a steam-boiler, of two closed tanks for receiving water, a water-actuated motor between said tanks, a pipe from the boiler to each tank, pipes from the latter to the motor, valves in said steam-pipes, and in the pipes leading from the tanks to the motor, means operated by the movement of the water in the tanks for automatically operating said valves, whereby the steam-pressure is shifted from one tank to the other, and the flow of water from one tank to the other is reversed without reversing the direction of its movement through the motor, substantially as described.

2. The combination with two closed tanks adapted to receive a liquid, of a pressure-generator, a pipe therefrom having branches extending to and connected with said tanks, a motor, pipe connections from each tank to said motor, valves in said pipe connections, and a valve in the pipe from the generator, located at the junction of the branches thereof; connections between said valves and means actuated by the movement of water in said tanks to operate said valves, whereby pressure from the generator may be shifted from one of said tanks to the other, and the flow of water between said tanks simultaneously reversed, without changing the direction of rotation of the motor, substantially as described.

3. The combination of a pressure-generator, of two closed tanks for receiving a liquid, a motor, pipe connections from one of said tanks to the other, and from each of them to said motor, a pipe from said generator having branches extending to each tank, a valve

in the generator-pipe at the junction of its branches thereof, valves in the connections between the tanks, and connections between said valves; a pressure-actuated piston connected with one of said valves, and means

5 connected with the valve of said piston and operated by the movement of water in said

tanks to simultaneously effect the operation of the valves in said pipe connection, substantially as described.

FREDERIC E. WELLS.
